GUIDING MEANS FOR GRINDING DRILLS

Albert C. Moorefield, Hawthorne, Calif.

Application February 9, 1943, Serial No. 475,245

9 Claims. (Cl. 51—219)

This invention relates to guiding means for facilitating the grinding of points of drills. The grinding of the points of drills, and particularly those of small diameter, is a source of considerable difficulty and inconvenience in machine shops, as it is very difficult to hold and properly support a drill of small diameter when grinding its point, and it usually requires considerable practice to develop sufficient skill in a mechanic to enable him to properly grind a drill-point. Furthermore, even where skilled mechanics are employed, the "personal" equation enters very largely in the grinding operation, the result of which is that the drills are not uniformly sharpened.

The drills referred to are a type known as twist drills, and the bodies of these drills have a high pitch helical groove extending down the same to a point, which is substantially conical, but with the "cone" point ground in slightly from the cone back of the cutting edge.

An object of the present invention is to provide guiding means including a rest and means cooperating with the rest in order to facilitate the grinding of a point of a twist drill such as referred to above.

Another object of the invention is to provide a rest with means cooperating with the same to adapt the rest to the grinding of the points of the drills of different diameters.

Another object of the invention is to provide guiding means including the rest and a holder with coordinated means on the rest and on the holder for facilitating the grinding of the drill-point by applying the same to the rest, and moving the holder laterally while guided on the rest to effect the grinding operation on the drill-point.

Another object of the invention is to provide means on the holder for the drill, which will facilitate the setting of the drill-point as regards the length to which it extends from the holder, so as to enable the same to cooperate with the rest when the drill-point is being ground.

Another object of the invention is to provide the holder with simple means for insuring that when the holder and the drill are applied to the rest, the drill will be prevented from rotating on its own axis, thereby insuring uniform grinding of the drill-point and precisely at the areas desired.

Further objects of the invention will appear hereinafter.

The invention consists in the novel parts and combination of parts to be described hereinafter.

all of which contribute to produce an efficient guiding means for grinding drills.

A preferred embodiment of the invention is described in the following specification, while the broad scope of the invention is pointed out in the appended claims.

In the drawing:

Fig. 1 is a plan of a portion of a tool grinder, certain parts being broken away, and illustrating a drill rest and guiding means embodying my invention, and supported adjacent to the side face of the grinder wheel.

Fig. 2 is a section taken in an inclined plane disposed substantially at right angles to the upper face of the body or body-plate of the rest on which the drill lies when being ground or sharpened. This view indicates a portion of the side face of the grinding wheel broken away and indicated in section, and in this view also the body of the holder for the drill, is broken away.

Fig. 3 is a plan of the holder removed from the rest and illustrating a drill held in the holder with the gauge of the holder positioned so that it will cooperate with the drill to indicate the proper degree of extension of the drill beyond the forward end of the holder, and also the proper oriented position of the drill on its own axis for proper grinding.

Fig. 4 is a cross-section taken on the line 4—4 of Fig. 3, and looking toward the rear end of the holder.

Fig. 5 is a plan of a guard that I prefer to employ on the holder at its forward end for assisting in guiding the holder and the drill on the rest when the drill is being sharpened, and which operates to prevent the drill from becoming oriented on its own axis away from the proper position in which it should be held.

Fig. 6 is a vertical section taken about on the line 6—6 of Fig. 1, and illustrating approximately the relation of the axis of the drill to the plane of the abrading face or side of the grinding wheel. In this view the body of the drill is broken away; a portion of the supporting edge of the rest is illustrated in section.

In practicing the invention, I provide guiding means which is preferably supported on a shelf or horizontal plate 1 of a frame 2 that supports an abrading or grinding wheel 3. In practice, I prefer to attach my device so that the point of the drill 4 will be applied to the flat side face 5 of the grinding wheel. In the present instance, I provide a bracket 6 having a foot 7 that may be attached on the support or shelf 1 by any suitable means such as machine screws 8. This

bracket 6 is formed with an upwardly extending shank 9 that flares out above to form a plate-like extension or "plate" 10 which is formed with curved guiding means adjacent its outer edge, that is to say, the edge that is remote from the abrading face 5. In the present instance, I form this guide plate 10 with a curved edge 11, the outer portion 12 of which is an arc struck on a radius, having its center substantially at the point 13 which would be substantially at the point 15 of intersection of the axial line 14 of the drill 4 with the side face of the grinder when the drill is applied on the rest ready to be ground; the portion of this curve that approaches the grinding face 5 deviates, however, from this arc so as to produce a cam edge 15 that permits the point 16 of the drill 4 to move nearer to the abrading face 5 if the drill is swung toward the right as viewed in Fig. 1. The inner edge 17 of this inclined plate 10, is substantially straight and lies substantially parallel with the face 5 and quite close to it.

The drill 4 is preferably held in a holder 18 which is an elongated block as indicated in Fig. 3. In Fig. 3 the holder is viewed from its under side. The body of this holder has a chamber or socket 19 extending completely through it to enable the drill to be inserted from one end and clamped therein by means of a set screw 20 (see Fig. 4). The forward end or nose 21 of this holder is guided along the curved edge 12, 15, when the drill is being ground. And, moreover, the body 18 is provided with means for setting the drill so that it extends the proper amount for a proper grinding at the forward end of the holder. For this purpose I provide the body of the holder with a movable gauge 22 which, in the present instance, is of bifurcated form and secured pivotally to the holder by means of a pin 23 (see Fig. 4) that projects outwardly on each side, and which pivotally attaches the two forks of this gauge. At the outer end of the gauge a cross-bar or cross-head 24 connects the two forks, and the outer edge 25 of this stirrup 24 is at a predetermined distance from the nose 21 of the body 18 for setting the drill-point; and in order to insure that the drill will be attached in the proper oriented position for grinding with this attachment, the edge 25 is provided with a base mark 26. When the drill is set, this base mark should substantially register with the cutting edge 27 at the drill-point, that is to say, the edge 27 is the cutting edge formed at the conical tip of the drill. After the drill-point has been set and clamped in the position illustrated in Fig. 3, the cross-head or stirrup end 24 of the gauge 22, is then swung around on the pivot pins 23 so that this gauge occupies a reverse position as indicated in Fig. 1. In this position the drill should be laid upon the upper face of the plate 10 about perpendicular to face 5, and the holder 18 is then swung to the right to grind the point of the drill. After grinding the side of the drill-point that is then presented to the abrading face 5, the holder should be turned over to an inverted position with the set screw 20 located below, and this operation repeated.

The degree of the cone face 28 that is formed on the drill, is determined substantially by the angle formed between the axis of the drill and the vertical face 5 of the abrading wheel. This is indicated in Fig. 6 which is a section on the line 6-6 of Fig. 1. When the rear portion or butt end of the drill is swung over toward the face 5, the cone face 28 of the drill is cut back

5 to form necessary clearance to give the drill a proper cutting point. A skillful mechanic can hold the holder 18 accurately in the position indicated, and also exactly in an inverted position to this in sharpening the drill, thereby insuring uniformity because such a skilled drill grinder would not orient the drill on its axis in doing this except to invert the holder. But if desired, means may be provided for insuring that a mechanic not so skillful, will hold the holder fixed with respect to the axis of the drill in grinding it. For this purpose I may provide a collet or auxiliary holder 29 which is in the form of a piece of bent strap metal for presenting two forks 30 with a cross-head 31 connecting the same. This cross-head 31 has an opening 32 in it that fits substantially to the diameter of the drill being ground. The forks 30 extend inwardly in the chamber 19, and if desired, these forks and the adjacent face of the chamber 19 may be provided with yielding interlocking means for holding the collet 29 in place when it has been inserted. This can be accomplished by pressing a depression or rudimentary socket 33 into the outer face of either one or both of these forks 30, and forming a corresponding small projecting nib on the inner face of the socket or chamber 19. The forks 30 would of course have some resiliency and tend to spread slightly so as to cause the socket 33 to engage the nib when the collet 29 has been inserted sufficiently far into the holder 18.

25 In the inserted position of the collet 29, its forward end will project slightly over the upper face of the upper plate 10 in the manner indicated in Figs. 1 and 2, and as long as the grinder holds the side of this collet down against the upper face of the plate, no orientation of the drill on its longitudinal axis can take place.

30 In order to adapt the device for operating on drills of different diameter and with equal accuracy, I prefer to provide a center stop 34 in the form of an upwardly projecting spur that projects above the surface of the guide plate 10, and means is provided for adjusting this spur in a lateral direction across the plate and in a general direction substantially at right angles to the axis of the drill in the position in which it would be placed on starting a grinding operation. For this purpose this centering stop is preferably formed as a lateral spur on a threaded shank 35, or screw, which extends through a threaded collar or nut 36, said collar mounted for rotation in a clearance slot 36a formed in the plate. Adjacent to this collar 36, a neck 37 of reduced diameter is provided, at which a keeper plate 38 is attached by means of a screw 39 to the upper face of the plate 10. This keeper holds the nut 36 in position. Beyond the reduced neck 37 the material of the neck is enlarged to form a dial 40 carrying a micrometer scale; between this dial and the neck a cone face 41 is formed with scale lines registered with the numbers on the dial, and these scale lines may register with a zero mark or base line 42 formed on the keeper or strap 38. Beyond the dial a knurled head or disc 43 is provided to facilitate the rotation of the nut 36 to cause the threaded shank 35 to move in or out to adjust the center stop 34 inwardly for smaller drills, or outwardly for larger drills. And, if desired, the upper end of the keeper plate 38 may be provided with a dowel pin 44 for assisting in holding this plate 38 in its proper alignment. This plate 38 operates as a friction brake on the collar 37 so that the collar 36 will remain in any position in which it is adjusted.

The grinding wheel 3 may be mounted in a bearing 3a, and its shaft may carry a pulley 3b which can be rotated by a belt 3c. However, any suitable means may be employed for rotating this grinding wheel.

If desired, the intermediate circumferential zone of the plate 10 may have a depression or recess 10a formed therein so that the drill is supported on the flat surfaces or zones on opposite sides of this depression.

Many other embodiments of the invention may be resorted to without departing from the spirit of the invention.

What I claim is:

1. In guiding means for facilitating the grinding of a drill-point on an abrading face, the combination of a relatively fixed rest having an upper face disposed in a plane inclined with relation to the abrading face against which the point of the drill is presented, said rest having a curved guide remote from the abrading face, a relatively fixed centering stop carried by the rest for guiding the side of the drill adjacent to, but removed from, its sharpened point so that the "cone" point of the drill is located between the stop and the abrading face; and means secured to the drill adjacent the said curved guide for riding along the same in sharpening the drill, all of said parts cooperating to enable the drill to be swung in each direction from its mid-position on the rest to sharpen the inclined face of the drill point on both sides of its axis.

2. In guiding means for facilitating the grinding of a drill-point on an abrading face, the combination of a relatively fixed rest having an upper face disposed in a plane inclined with relation to the abrading face against which the point of the drill is presented, said rest having a curved guide remote from the abrading face, a relatively fixed centering stop carried by the rest for guiding the side of the drill near its point and about which the forward end of the drill swings in the sharpening movement; means for adjustably moving said centering stop laterally to adapt its position to the diameter of the drill being sharpened; and means secured to the drill and capable of being guided along said curved guide, said curved guide operating to permit the point of the drill to approach the said abrading face when the rear end of the drill is swung toward the abrading face while maintaining the point of the drill against said centering stop.

3. In guiding means for facilitating the grinding of a drill-point constructed as defined in claim 1, including adjusting means associated with the relatively fixed centering stop for adjusting the said stop laterally to adapt the said guiding means for grinding drills of different diameter, said adjusting means having a scale associated therewith, the reading on which operates as a guide for setting the centering stop to different positions to correspond with different drill diameters; said parts all cooperating so that the forward end of the drill swings around on the side of the stop during the sharpening movement of the drill.

4. In guiding means for facilitating the grinding of a drill-point on an abrading face, the combination of a relatively fixed rest having an upper face disposed in a plane inclined with relation to the abrading face against which the point of the drill is presented, said rest having a curved guide remote from the abrading face, a relatively fixed centering stop for engaging the side of the drill adjacent its point, said rest having guiding means

extending transversely thereon along which the centering stop may move, means for adjusting, and indicating the position, of the stop in said guiding means to adapt the stop for grinding drills of different diameters, and means secured to the drill adjacent the said curved guide for riding along the same when sharpening the drill.

5. In guiding means for facilitating the grinding of a drill-point against the substantially flat abrading side face of a grinding wheel, the combination of a relatively fixed rest, a holder unattached to the rest and capable of clamping the butt end of the drill, said rest having means for enabling the drill to be held on the rest with the axis of the drill inclined to the horizontal in the vertical plane passing through the axis of the drill and also in a plane that is inclined to the plane of the side face of the grinding wheel, a relatively fixed stop carried by the rest for engaging the side of the drill back from, but adjacent to, the sharpened point, said rest and said holder having cooperating means enabling the holder and the butt end of the drill to be swung laterally in both directions and toward the grinding face in grinding the drill-point.

6. In guiding means for facilitating the grinding of a drill-point on an abrading face, the combination of a relatively fixed rest having an upper face disposed in a plane inclined with relation to the said abrading face, a centering stop mounted on the rest with means for adjusting the same laterally on the rest and toward or from the grinding face to adapt the position of the stop for grinding the points of drills of different diameters, said rest having a curved guiding edge located on its side remote from the grinding face, and a holder for clamping the body of the drill when the drill is held lying on the rest, the forward end of the said holder having means for engaging said curved edge when the holder is swung laterally and toward the grinding face to grind the drill-point.

7. In guiding means for facilitating the grinding of a drill-point on a grinding wheel, the combination of a rest supported with an edge adjacent the face of the wheel, said rest operating as a guide for a drill holder independent of the rest, supported in the operator's hand, said rest having a curved guide edge remote from the wheel against which the operator presses the forward end of the holder, and a center stop projecting up from the rest adjacent the first-named edge for engaging one side only of the drill-point when the drill is held on the rest and pressed against said curved guide edge, said curved guide operating to permit the drill-point to swing around it and to approach and engage the face of the wheel when the butt end of the drill is swung toward the wheel.

8. In guiding means for facilitating the grinding of a drill-point on an abrading face, the combination of a relatively fixed rest having an upper face disposed in a plane inclined with relation to the said abrading face, said rest having a curved guide remote from the abrading face, a holder for carrying the butt portion of the drill, said holder being independent of the said rest, freely movable, and supported solely on said inclined face, so that the inclination of said face determines the angular relation of the drill to the abrading face, means associated with the holder for facilitating the setting of the drill in the holder so that the drill will be held in the holder so as to enable the drill-point to engage the abrading face, said holder having means at its forward end

for engaging and riding along the said curved guide when grinding the drill-point, and means carried by the rest and projecting above the plane of the upper face of the rest for guiding the side of the drill adjacent to, but removed from, its sharpened point, to determine the position of the axis of the drill when the said holder is applied to said curved guide preparatory to grinding the drill-point.

9. In guiding means for facilitating the grinding of a drill-point on an abrading face, the combination of a relatively fixed rest having an upper face disposed in a plane inclined with relation to the said abrading face, said rest having a curved guide remote from the abrading face, a holder for attachment to the butt portion of the drill, said holder being independent of the said

rest, freely movable, and portable in the operator's hand so that it may be pressed down by manual force against said rest, said holder including a body and a gauge member pivotally mounted on the body of the holder, capable of assuming a position located toward the forward end of the holder to indicate the proper position of the drill-point when securing the same in the holder, and capable of being swung around to another position adjacent the rear end of the holder when the holder is to be guided along the curved guide when grinding the drill-point, said holder having means at its forward end for engaging and riding along on said curved guide when grinding the drill-point.

10

ALBERT C. MOOREFIELD.
